(57) **CLAIM**

I claim the ornamental design for a self-standing walking stick with light base, as shown and described.

DESCRIPTION

FIG. 1 is a perspective view of the self-standing walking stick with the lighted base of the present invention.

FIG. 2 is a top plan view of the walking stick.

FIG. 3 is a right side elevation view of the walking stick.

FIG. 4 is a front elevation view of the walking stick.

FIG. 5 is a left side elevation view of the walking stick.

FIG. 6 is a rear elevation view of the walking stick; and,

FIG. 7 is a bottom plan view of the walking stick.

The broken lines shown in the drawings are for illustrative purposes only and form no part of the claimed design.
